(57) CLAIM

The ornamental design for a golfer's exercise stretching rack, as shown and described.

DESCRIPTION

FIG. 1 is a perspective view of a golfer's exercise stretching rack showing my new design;

FIG. 2 is a front elevational view thereof, the rear elevational view, left-side elevational view, and right-side elevational view all being a mirror image thereof;

FIG. 3 is a top plan view thereof; and,

FIG. 4 is a bottom plan view thereof.

The broken lines showing a ground surface in FIG. 1 depict environmental matter and form no part of the claimed design.
